UNITED STATES PATENT OFFICE.

BOUGHTON T. NOBLE, OF PLANTSVILLE, CONNECTICUT, ASSIGNOR TO CLARK BROS.
BOLT CO., OF MILLDALE, CONNECTICUT, A CORPORATION.

METHOD OF FORMING BOLTS.

Application filed June 26, 1922. Serial No. 571,022.

To all whom it may concern:

Be it known that I, BOUGHTON T. NOBLE, a citizen of the United States, residing at Plantsville, in the county of Hartford and State of Connecticut, have invented a new and useful Improvement in Methods of Forming Bolts; and I do hereby declare the following, when taken in connection with the accompanying drawings and the characters of reference marked thereon, to be a full, clear, and exact description of the same, and which said drawings constitute part of this application, and represent, in—

Fig. 1, a plan view of bolt-forming dies constructed in accordance with my invention, and shown with the stock arranged between them, preparatory to the upsetting operation.

Fig. 2, a side view of the inner faces of one of the upsetting-dies and corresponding backing-die.

Fig. 3, a rear view with the backing-dies removed.

Fig. 4, a plan view, partly in section, showing the position of the dies at the completion of the bolt-forming operation.

Fig. 5, a view similar to Fig. 2, showing the dies in the position of the parts in Fig. 4.

Fig. 6, a plan view of one of the bolts formed in accordance with the method and with the dies herein described.

This invention relates to an improvement in method of forming bolts, and by the term "bolts," as herein used, I wish to be understood as including bolts, rivets, studs, or devices for similar purposes.

The object of this invention is to form a bolt from a piece of stock smaller in diameter than the diameter of the finished bolt, leaving the end to be threaded of the original diameter of the stock, and then rolling threads on the unenlarged portion so as to bring the diameter of the threads equal to the diameter of the body of the bolt, and the invention consists in the method as hereinafter described and particularly recited in the claim.

In carrying out my invention I employ a pair of upsetting-dies 10 and 11, provided in their adjacent faces with semi-circular grooves 12 and 13, together forming an opening corresponding mainly to the diameter of the shank of the bolt to be formed.

The rear faces of the upsetting-dies 10 and 11 are formed with pockets 23 and 24 to receive springs 25 and 26, which are seated in pockets 27 and 28 of backing-dies 29 and 30, the adjacent faces of which are formed with grooves 31 and 32, corresponding to the size of the wire blank 33 from which the bolt is to be formed and with a flaring mouth. The stock or blank 33, from which the bolt is to be formed, is fed between the backing-dies and the upsetting-dies, while there is a space between them maintained by the springs 25 and 26, the length of the blank being such that it will not only extend through the two pairs of dies and the space between them, but projects beyond the upsetting-dies sufficiently to furnish material for the head 21 and a part of the shank 20. The two pairs of dies are then brought together to grip the stock between the backing dies. The dies are then moved into line with the usual heading punch 34, which crowds the upsetting-dies against the backing-dies, upsetting the blank, so as to fill the recesses 12 and 13 from opposite ends, and, at the same time, form the head 21. If necessary, a second blow of the punch may be given upon the stock to fully complete the forming operation, which, however, is substantially performed by a single blow. After the bolt is formed, the dies are separated, the bolt ejected, and another piece of stock fed in its place,—all as usual in the manufacture of bolts and similar articles used in bolt-forming machines. The end of the blank may then be rolled to form threads 22 which will bring the diameter of this end of the bolt equal to the diameter of the body portion of the bolt.

I thus produce, by practically one operation, a bolt blank having its main portion of a diameter larger than the diameter of the stock from which it is formed. The dies for forming bolts, etc., above disclosed, are not claimed herein, but are made the subject of a separate application, filed June 26, 1922, Serial No. 571,023.

I claim:

A method of forming bolts, consisting in passing the stock between a pair of backing-dies having grooves mainly corresponding to the size of the stock and with a flaring mouth and between a pair of upsetting-dies having grooves of greater diameter than the

stock, bringing the dies together so as to grip the stock between the backing-dies, then applying pressure in the direction of the length of the stock, whereby the stock is upset to fill the upsetting-dies and thereby increase the diameter of the main portion of the shank.

In testimony whereof I have signed this specification in the presence of two subscribing witnesses.

BOUGHTON T. NOBLE.
